UNITED STATES PATENT OFFICE.

HORATIO S. EARLE, OF DETROIT, MICHIGAN.

SCREEN FOR SAND AND GRAVEL.

1,418,545.

Specification of Letters Patent. Patented June 6, 1922.

Application filed December 30, 1918. Serial No. 268,917.

To all whom it may concern:

Be it known that I, HORATIO S. EARLE, a citizen of the United States, residing at Detroit, county of Wayne, State of Michigan, have invented a certain new and useful Improvement in Screens for Sand and Gravel, and declare the following to be a full, clear, and exact description of the same, such as will enable others skilled in the art 10 to which it pertains to make and use the same, reference being had to the accompanying drawings, which form a part of this specification.

This invention relates to screens for sand, 15 gravel and other material, and its object is to provide a screen that is comparatively inexpensive in character and to provide one in which there is a double screening effect. That is—the material, as sand and gravel, is 20 discharged into the interior of the screen discharges material up to a predetermined size onto an outer fine screen, the larger parts being discharged into one receptacle and that which passes the fine screen being 25 discharged into another receptacle. The invention further has for its object a method of holding and supporting the circumferential wire forming the outer screen in pre-disposed relation with the inner screen member 30 which is preferably formed of a foraminous sheet of metal. A further object is to provide a cheap and efficient spacing device for holding the circumferential wires forming the outer screen. These general objects 35 and the several novel features of the invention are hereinafter more fully described and claimed and shown in preferred form in the accompanying drawings in which—

Fig. 1 is a vertical longitudinal section of 40 a screen embodying my invention.

Fig. 2 is an enlarged cross section of a part of the inner and outer screen members showing the means of supporting the outer screen member by the inner member.

Fig. 3 is a plan view of a portion of the outer screen members showing the method of supporting the wires in predetermined relation.

Fig. 4 is a detail in perspective of a part 50 of the spacing member.

Fig. 5 is a plan view of a portion of one of the spacing bars.

Fig. 6 is an elevation of the member used 55 in supporting the wire fabric on the inner screen member.

The screen as shown in Fig. 1 is preferably

cylindrical in form and may be made greater or less length as may be desired by adding other cylinders in endwise relation on the shaft. The principle of the invention, however, is disclosed in the single cylinders here shown. The screen is supported on a shaft 1 which may be conveniently supported at each end in bearings in the supporting members 2 and 3 to hold the shaft at an inclination to the horizontal and provided with means for rotation thereof (not here shown). The inner screen member is formed preferably of foraminous sheet metal 4 of cylindrical form having a series of apertures 5 therein of predetermined size. Preferably, for sand and gravel, these apertures are about three-fourths of an inch in diameter, and if desired, a succeeding cylinder may be attached to the shaft at the lower end of the 75 cylinder 4 having apertures of the same or different sizes, such additional cylinder being indicated by the dotted lines 6 shown on Fig. 1. This cylinder 4 is supported by two or more spiders 7 having radial arms shaped 80 at the end to pass through apertures in the plate and to be secured thereon by the nuts 8.

Surrounding this inner foraminous cylinder 4 is a cylinder 9 formed of wires extending circumferentially thereabout and spaced 85 a short distance from the wall of the cylinder 4. These wires may be spaced quite close together longitudinally of the cylinder as is required to produce the desired fineness of the screened material. The method of 90 spacing the wires is shown more particularly in Fig. 3 from which it will be observed that a series of angle bars 10 extend longitudinally of the cylinder, and these bars are shown in detail in Figs. 4 and 5. 95 From the detail it will be observed that the angle bar is punched, the opposite members of the angle having apertures 11 and 12 therein of a diameter to receive the wires 13. The metal between the two apertures 11 and 100 12 is slit transversely, and the ends thereof turned upward as indicated in Fig. 4 providing upwardly projecting portions or lugs 14 and 15. The bars are punched with the parts 14 and 15 upset as indicated to allow each 105 strand of the wire to be inserted into the bar and thereafter these lugs are turned downward as indicated at the right hand side of the Figs. 4 and 5 tightly engaging the wire. For this purpose the wire at equidistant 110 points thereon is provided with a depression or outwardly bent portion 16 which portion

16 only seats in the apertures in the bar. This construction enables the use of a spacing member which may be formed of metal light in weight, strength resulting from the 5 form of the bar which prevents the buckling thereof. Each wire strand 13 is independent of each other strand, and the ends thereof 17 and 18 are provided with hook portions which are inserted through a slot in a plate 10 19 as shown in Fig. 2. With the construction described, particularly the angle plates or bars, the point of the plates on the interior of the screen do not extend above the inner surface of the wire members so the 15 bars do not project into the space between the wire and the inner cylinder 4.

The wire fabric may be supported on the inner foraminous cylinder by means of split bolts 20 which are somewhat of the 20 character of a cotter pin having an aperture 21 at one end of a size to practically fit a wire. The bolt, being longitudinally split as shown, may be opened to allow insertion on the wire until the wire rests in the aperture. The two legs of the bolt are brought 25 together and a cylindrical headed member 23 threaded thereon. The end of the bolt is then inserted through an aperture in the plate 4 and the cylindrical member 23 30 turned inward until the head engages the plate, whereupon further turning by means of the slotted head 50 of the member forces the bolt 20 outward and this movement of all the bolts 20 stretches the wire fabric to 35 place. The inner end of the cylinder 23 is preferably threaded and a nut 22 placed thereon after the wire fabric has been positioned as stated, and a lock washer may be employed beneath the nut 22. By reason 40 of the practical impossibility of manipulating a nut positioned between the foraminous plate and the wire fabric, the mechanical arrangement above stated may be employed which may be manipulated from the interior 45 of the foraminous cylinder 4. These supporting members or bolts 20, being of the shape described, present little obstruction to the passage of material longitudinally of the screen during its rotation. There 50 are several of these supporting members 20 as indicated in Fig. 1, there being three or more such members in alignment longitudinally of the screen and several such lines 55 equidistantly spaced about the cylinder 4. By this means the screen fabric is securely held in desired spaced relation with the inner cylinder, and the obstruction presented to a flow of material is negligible.

In operation, the material from a sand 60 or gravel bank is discharged into the interior of the screen 4 by means of a chute 25 of suitable design. This inner cylinder is of a strength to sustain the weight of material and protects the outer screen member 65 and the outer screen member may therefore

be of finer wire as there is little liability of disarrangement or distortion of the wires by weight of material discharged thereonto. By use of the foraminous plate the only material discharged into the outer wire screen 70 is that which may pass the inner screen member and thus the outer screen is relieved from a load of all that material coarser than what may pass the inner screen. Both the screen members at the lower end discharge into a conduit 26 while the material that may pass through the wire member is discharged directly therebeneath into a bin 27 or it may be discharged into a conduit of 75 any character and all the material that is 80 coarser than what may pass through the outer screen is discharged into the conduit 26 or separate conduit as desired.

By the construction described, I am able 85 to use a wire of less strength than would be required if all material were initially discharged thereonto, and by the construction described, the screen is very cheaply assembled with the wires uniformly spaced. The cross bars may be very light in weight 90 due to their form which prevents liability to distort in use. Furthermore, the wire strands are very securely held in the desired spaced relation and the space between the two screen members is practically free from 95 obstruction to flow of material except that of the bolt members 20 which are of such character as to obviate the accumulation of any great quantity of material behind the same.

Having thus briefly described my invention, what I claim is—

1. A screen fabric comprising a series of circular wire strands, a series of angle bars 105 extending transversely of the wire strands and having equidistantly spaced seats therefor, the seats being formed by providing apertures in each leg of the angle adjacent the junction point thereof, the metal between the apertures at the junction of the 110 two legs providing a lug adapted to be bent over and hold the strand in its seat, each strand having an outwardly bent portion for seating in the bar, the relationship of the bars and strands being such that the 115 bar is positioned outside the area circumscribed by the inner face of the wire strands.

2. A screen fabric comprising a series of circular wire strands, a series of bars of 120 angle cross section in equidistantly spaced relation extending longitudinally of the fabric and having equidistantly spaced seats for the strands, the seats being formed by providing apertures in each leg of the angle 125 in alignment transversely thereof to receive the strand, the strand having an outwardly bent portion for seating in each bar and the portion between the apertures of the bar being slit and bent upwardly providing lugs 130

adapted to be turned downward over the wire to secure it in position on its seat, the outwardly bent portions of the strands positioning the inner face of the angle bar 5 outside the circle formed by the inner face of the strands.

3. A screen fabric consisting of a series of equidistantly spaced wires and a series of bars extending transversely of the bars, the 10 bars being provided with seats for the wires and the wires having outwardly bent por-

tions equidistantly spaced longitudinally thereof for engaging in the said seats, the bars having integral lugs thereon adapted to be forced down over the bent portions 15 and the bent portions positioning the inner face of the bar below the inner side of the wire members.

In testimony whereof I sign this specification.

HORATIO S. EARLE.
